(57) **CLAIM**

The ornamental design for a rivet gun safety guard, as shown
and described.

DESCRIPTION

FIG. 1 is a front perspective view of a rivet gun safety guard
showing my new design;

FIG. 2 is a rear perspective view thereof;

FIG. 3 is a front elevation view thereof;

FIG. 4 is a rear elevation view thereof; and,

FIG. 5 is a right side elevation view thereof, to which the top
plan and bottom plan views are identical and the opposing
left side elevation view is a mirror image.
